Inventor:

Julius Singer,
By his Atty, W. W. Richard.

UNITED STATES PATENT OFFICE.

JULIUS SINGER, OF NEW YORK, N. Y.

PAN-RACK.

1,294,947.

Specification of Letters Patent. Patented Oct. 25, 1921.

Application filed November 24, 1919. Serial No. 340,300.

To all whom it may concern:

Be it known that I, JULIUS SINGER, a citizen of the United States, residing in New York, in the county of the Bronx and State of New York, have invented certain new and useful Improvements in Pan-Racks, of which the following is a specification.

This invention relates to racks for utensils and articles of the kitchen and household kind which are of frequent and daily use, but are difficult to store or dispose of when not in use, and an object of the invention is to provide a simple, convenient and inexpensive means for the disposal of such utensils and articles when not in use. A further object is to provide a rack of this character which may be placed in a standing position, or may be attached to the wall of the kitchen, or to the door or side of a closet, preferably in a position near the kitchen range. A further object is to provide a rack of this character for the limited kitchen space of apartment houses, dining cars or vessels.

25 Referring to the drawings forming part of this specification:

Figure 1 is a front elevation, partly in perspective, of the rack showing various kitchen utensils or articles disposed thereon.

30 Fig. 2 is a fragmentary sectional view showing a means for attaching a transverse slat of the rack to an upright or support of the rack.

Similar characters refer to similar parts throughout the several views.

The rack which may be of wood or suitable metal, comprises uprights or supports A A, provided at the lower ends with feet B B, which feet when the rack is intended 40 to stand upon the floor should be of sufficient area to maintain the rack steady in a standing position, or the feet B B, may be arranged for attachment to the floor by screws 10, or other suitable means.

45 The upper ends of the uprights or supports A A, are provided with means, such as the screws 11, for attaching the rack to the kitchen wall or other vertical surface.

The uprights or supports A A, are connected by transverse slats C C, comprising a face portion D D, and a rear portion E E, the respective ends of the face portions C C, being separably secured to the uprights or supports A A, in any suitable manner, such 55 as the dowel pins 12, which engage in holes 13, in the uprights or supports, Fig. 2.

The rear portions E E, of the transverse slats C C, are shorter than the face portions D D, and are provided with ends 14, extending forwardly substantially at right angles 60 to the rear portions, such ends being secured to the rear side of the face portions by suitable means, not shown, to space the face and rear portions apart and to provide a longitudinal space 15, between the face 65 portions D D and the rear portions E E, of the slats, for the purpose later set forth, the rear portions E E thus being supported by the face portions D D.

The face portions D D, are provided on 70 the forward side thereof with means, such as the hooks 16, for suspending the utensils or articles thereby.

A flat horizontal surface, or shelf-surface, such as the shelf F, is arranged near the 75 bottom of the rack, or in other suitable position and is separably secured at its ends by suitable means not shown, but preferably by dowel-pins such as 12 engaging holes such as 13 in the uprights or supports A A. 80

By thus separably connecting or securing together the uprights or supports A A, transverse slats C C and the shelf surface such as F, I provide a knock-down rack, or rack comprised of separable parts which are held 85 in normal but separable operative relation by engagement of the parts, and which rack when in knocked-down form is capable of being readily carried or conveniently stored, and when desirable can be easily set up or 90 arranged in operative relation of the parts.

A feature of my rack is that the parts when separably secured in normal operative relation may be so held and prevented from being separated by the attachment of the uprights or supports A A by means, such as the screws 10, engaging the lower ends of the uprights or supports and engaging a horizontal surface, such as the floor of a building, and by means, such as the screws 11, engaging the upper ends of the uprights or supports and engaging a vertical surface, such as a side wall, the parts comprising the rack, thus being held inseparable in their relation to each other. 100

In use, utensils or articles such as the dish-pan and frying pan shown, are hung by their handles to the hooks 16, milk-cans, pots, kettles and the like having a large base surface being placed on the shelf F, while 110 pot-lids, pans, and similar slim or thin utensils or articles which are not readily

suspendible, but which are receivable in the interspaces 15, are placed therein, in the case of a pot-lid G, such as shown, the button or handle g thereof resting upon or engaging the upper edge of a face portion D, while the lower portion of the pot-lid which is received in the interspace 15, engages at an angle the front face of the rear portion E of the transverse slat C, to retain the pot-lid in the interspace 15, utensils or articles of this slim or thin kind which are of different diametric size being thus receivable in the interspace 15 and in lapping relation if necessary.

15 From the foregoing description it is obvious that the rack may be provided with more than two transverse slats, such as C C, and more than one shelf-surface, such as the shelf F, and I do not restrict myself to the 20 number of transverse slats or the single-surface shown.

Having thus described my invention, I claim:

25 1. A rack comprising a pair of uprights, and a plurality of transverse slats for spacing the uprights apart; each transverse slat consisting of a face portion and a rear portion, the ends of the face portion being separably secured to the inner sides of the

uprights; the rear portion of each slat having forwardly projecting ends located between the uprights and bearing against and secured to the rear surface of the face portion for providing space between the rear surface of the face portion and the front surface of the rear portion for supporting non-suspendible utensils therein.

2. A rack comprising a pair of uprights, and a plurality of transverse slats for spacing the uprights apart; each transverse slat 40 consisting of a face portion and a rear portion, the ends of the face portion being separably secured to the inner sides of the uprights, and the rear surface of the rear portion lying substantially in the vertical 45 plane of the rear edges of the uprights; the rear portion of each slat having forwardly projecting ends located between the uprights and bearing against and secured to the rear surface of the face portion for providing space between the rear surface of the face portion and the front surface of the rear portion for supporting non-suspendible utensils therein.

JULIUS SINGER.
